(57) **CLAIM**

I claim the ornamental design for a display screen with animated graphical user interface, as shown and described.

DESCRIPTION

FIG. 1 is a first image for a display screen with animated graphical user interface of multi-protection system; FIG. 2 is a second image thereof; and, FIG. 3 is a third image thereof.

The ornamental design which is claimed is shown in solid lines in the drawings. The broken lines in the drawings depict environmental subject matter only for illustrative purposes and form no part of the claimed design. The words and numbers shown in broken lines are unclaimed features of the graphical user interface.

The appearance of the transitional image sequentially transitions between the images shown in FIGS. 1-3. The process or period in which one image transitions to another image forms no part of the claimed design.
